US00D896218S

(12) **United States Design Patent** (10) **Patent No.:** **US D896,218 S**
(45) **Date of Patent:** **** Sep. 15, 2020**

(54) **COMPUTER**

(71) **Applicant:** **SIEMENS AKTIENGESELLSCHAFT**, Munich (DE)

(72) **Inventors:** **Ming Yuan Gao**, Chengdu (CN); **Di Fei Huang**, Chengdu (CN); **Xue Kang Li**, Chengdu (CN); **Ting Li Lan**, Chengdu (CN)

(73) **Assignee:** **SIEMENS AKTIENGESELLSCHAFT**, Munich (DE)

(**) **Term:** **15 Years**

(21) **Appl. No.:** **29/656,280**

(22) **Filed:** **Jul. 11, 2018**

(30) **Foreign Application Priority Data**

Jan. 12, 2018 (CN) 2018 3 0015300

(51) **LOC (12) Cl.** **14-02**

(57) **CLAIM**

The ornamental design for a computer, as shown and described.

DESCRIPTION

FIG. 1 is a front view of a computer, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a top, front and right side perspective view thereof. The features in the interior of the computer box seen through the square, circular and hexagonal openings are shown in solid lines for clarity of illustration, and form no part of the claimed design.

1 Claim, 7 Drawing Sheets
